UNITED STATES PATENT OFFICE.

GEORGE W. BEDBURY, OF PORTLAND, OREGON, ASSIGNOR OF ONE-HALF
TO A. E. BORTHWICK, OF SAME PLACE.

CAR-COUPING.

SPECIFICATION forming part of Letters Patent No. 269,999, dated January 2, 1883.

Application filed June 26, 1882. (No model.)

To all whom it may concern:

Be it known that I, GEORGE W. BEDBURY, a resident of the city of Portland, in the county of Multnomah and State of Oregon, have invented certain new and useful Improvements in Car-Couplings, of which the following is a specification.

My invention relates to a car-coupling in which the means of coupling or uncoupling cars is attained by constructing the draw-head of the car in two pieces, which perform the functions of draw-head, connecting-pin, and coupling by themselves.

The object of my invention is to construct a car-coupling which will be strong and simple in operation, and adapted to cars of uneven height, and in which a strong connecting link or bar can be used, thereby obviating the necessity of double links, heretofore required on mountain roads; and my invention consists—

First. In constructing the draw-head with the shank and tongue portion in one piece, with a suitable vertical projection thereon and two lateral projections, and the upper part comprising the top and both sides of the draw-head in another piece, which upper part is provided with slotted holes to fit upon the lateral projections of tongue or lower portion. These two portions shut together and form the draw-head and coupling.

Second. By constructing the link in the form of a strong bar, with pointed ends and hooked recesses adapted to fit into and with the portions of the draw-head.

Third. By attaching the upper or pivoted portion of coupling to a vertically-adjusting rod attached to car.

In the accompanying drawings, forming part of this specification, Figure 1 is a side view of two couplings or draw-heads with link coupled, the dotted lines showing the movement of the parts. Fig. 2 is a view in perspective of the connecting-bar. Fig. 3 is an end view of the coupling or draw-head, showing the upward motion of the pivoted part; and Fig. 4 is a sectional view of a car with the draw-head or coupling and vertical rod attached.

AA in Fig. 1 represent two of my coup-

lings or draw-heads, and B is the connecting bar or link.

C is the shank or tongue portion of the draw-head.

c is a vertical projection formed upon the upper side of shank C, and is for the purpose of preventing the connecting bar or link from going too far back when being coupled.

bb' are lateral projections formed upon shank C, upon which fit the slotted holes of upper portion, D, of coupling.

D is the upper portion of coupling or draw-head, and is constructed so as to fit over lower portion, C, and is pivoted upon the projections bb'. Just inside of the jaws portion D is constructed so as to form a pin or hook, c', and hold the connecting-bar when shut down upon it.

E is the vertical rod or shaft for operating the coupling or upper part of draw-head, either from the track or the top of the car. It is journaled in a box, e, on car, as shown in Fig. 4, and provided with a handle and lug, by which it can be lifted up and suspended.

The upper and lower portions, C D, in front form the jaws of the draw-head, as shown in Fig. 4.

The operation of my improved coupling and draw-head is as follows: When the cars are brought together the hook-like and grasping manner in which the upper part, D, holds the connecting bar or link B against tongue or shank C prevents the link B from dropping down, and it is presented to the opposite draw-head or coupling straight and level with the mouth or entrance. As the hook end of link enters, the pivoted upper portion, D, is raised until the hook passes the catch or inside of the jaws and catch c', when it at once drops to place and catches the hook of link B, which operation couples the car. When it is desired to uncouple, then the rod is lifted vertically, sufficient play being allowed rod E in box e to permit a forward and backward movement, according to the rise or drop of the part D of draw-head. The link or bar B is also provided with slotted openings to be used with the old style of hand-pin coupling. The weight of the part D, pressing down upon the part C of the

draw-head, insures the connection of the link therein to a certainty.

Having described my invention, what I claim as new, and desire to secure by Letters Patent, 5 is—

1. In combination, the tongue-shaped part C, having vertical projection c and lateral projections b b, and the upper part of coupling D, pivoted upon part C, operating as shown, and 10 for the purpose described.
2. In combination with parts C and D, con-

structed and operating as herein shown, the link B, for the purpose set forth.

3. In combination with tongue-shaped part C, the upper pivoted part of coupling D, adapted 15 to couple with the link B by its weight, substantially as herein shown and described.

GEORGE W. BEDBURY.
